RECEIVER AUTOMATIC VOLUME CONTROL
SWITCHKenneth W. Jarvis, New Rochelle, N. Y., assignor
to Radio Corporation of America, a corpora-
tion of Delaware

Application September 16, 1935, Serial No. 40,685

1 Claim. (Cl. 250—20)

My present invention relates to gain control arrangements for radio receivers, and more particularly to a radio receiving system provided with a switch for rendering the receiver automatic gain control network inefficient during periods of tuning in the desired station.

In normal non-automatic volume controlled receivers, it is the practice to tune to the desired station by tuning to the point of the loudest signal. As the selectivity characteristic of the receiver is generally quite sharp, this point of maximum volume is found quite easily. It is well known in the prior art that for maximum discrimination against undesired stations, this tuning to the peak of the selectivity characteristics, or frequency response characteristic, is quite necessary. The fidelity and quality of the received signals are also best when the receiver is tuned to this proper point.

As is well known automatic volume control is utilized in receivers of modern construction, in most cases, to eliminate the effects of signal fading. In such receivers the amplitude of the acoustic volume is maintained practically constant by automatically increasing the receiver gain whenever the incoming signal strength decreases. The control point for such automatic control is generally at, or near, the detector producing the final audio frequency signal. For this reason any change ahead of this point, such as signal fading, is compensated for to the extent of the automatic volume control.

Mistuning also normally reduces the signal intensity at the detector and the control point, and so brings into operation the automatic control, thus raising the acoustic level to its normal output; and this occurs even though the receiver is mistuned. Hence, with automatic volume control tuning to the correct point through apparent signal intensity is not possible.

It may, therefore, be stated that it is one of the principal objects of the present invention to enable such correct tuning to be obtained without sacrificing any of the advantages of automatic volume control.

Another important object of the present invention may be said to reside in the inclusion in a radio receiver of the type utilizing automatic volume control, of a manually actuatable switch mechanism for rendering inefficient the automatic volume control mechanism upon actuation of the tuning means of the receiver.

Still other objects of the invention may be said to reside in the general improvement of receivers utilizing automatic volume control so that they

operate in a manner rendering tuning simple, and more especially to provide such improvement in an economical and efficient manner.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1 graphically shows the operation of a receiver which does not embody the present invention.

Fig. 2 graphically illustrates the operation of a receiver employing automatic volume control.

Fig. 3 is a circuit diagram of a receiving system utilizing the present invention.

Fig. 4 is a voltage-current curve of the automatic volume control tube shown in Fig. 3.

Fig. 5 graphically indicates the magnitude of the volume control bias with respect to the signal producing it.

Fig. 6 shows a mechanical embodiment of the automatic volume control switch employed according to the present invention.

Referring now to the accompanying drawings, wherein like reference characters in the different figures indicate similar elements, in Fig. 1 there is shown in graphic manner the variation of "acoustic output" with "dial position" for the two methods of volume control used in a radio receiver. The full line curve 1 indicates the sharply selective condition of the receiver, and it will be seen that the acoustic output varies almost in proportion as the dial is rotated. The full line curve 1 represents the acoustic response when the receiving system does not utilize automatic volume control (hereinafter referred to as AVC) and a manual volume control device is used. The obvious point for correct tuning is at the point 2, quite easily determined with the given shape of curve 1. The broken line curve 3 represents the acoustic response when the receiver employs automatic volume control. It will be seen that in tuning away from the correct operating point 2 the receiver gain decreases.

However, the automatic volume control action tends to restore this gain by reducing the negative bias on the gain control electrodes of the signal amplifier tubes. As a result the acoustic output does not fall, but stays substantially con-

stant over a wide range of dial movement, as shown. The correct turning point 2 is almost impossible to find as a result of this action of the AVC mechanism.

In Fig. 2 there is shown the relation between "acoustic output" and "signal strength in micro-volts". The full line curve 4 shows the response with respect to the signal input. The signal input increasing from zero, the output rises as shown. At the point 5 the AVC action begins, and the curve flattens off. Without this AVC action the output would probably rise in the manner represented by the broken line 6. In the case of detuning the gain due to the frequency characteristic of the resonant circuits falls. The output would fall except that the AVC action compensates. Some point on the right hand side indicates the correct tuning point, while detuning corresponds to sliding back along the curve to the left; of course, eventually losing the signal despite the AVC action. At first the detuning causes very little loss in signal; it will be observed that the analysis in Fig. 2 confirms and explains that of Fig. 1.

Fig. 3 shows a portion of a radio receiving system embodying one form of the present invention. It will be understood that only such portions of the radio receiving system are shown as are necessary for a proper understanding of this invention. The numeral 7 indicates a tuned transformer feeding an amplifier tube 8. The primary of the transformer 7 may be coupled to one or more stages of radio frequency signal amplification, and it is to be understood that the receiver may be of the superheterodyne type, or of the well known tuned radio frequency type. For example, if the receiver is of the superheterodyne type, then the tube 8 may be one of the I. F. amplifier tubes, and the transformer 40 7 will then be preceded by the usual radio frequency amplifier and first detector stages. If the receiver is of the tuned radio frequency type, then each of the tunable circuits of the receiver will include variable condensers arranged in the well known uni-controlled manner.

The amplifier 8 feeds through the tuned transformer 9 a detector 10. The numeral 10' designates a source of positive potential which is included in the plate circuit of amplifier tube 8, and the input circuits of tubes 8 and 10 each include variable tuning condensers. Of course, if the receiver is of the superheterodyne type the condensers in the input circuits of tubes 8 and 10 will be fixed, and in that case the present invention is utilized in connection with the variable tuning condensers commonly employed ahead of the first detector tube. The detector tube 10 demodulates the amplified radio frequency signal, and the demodulated signal is transmitted to the subsequent audio amplifying network, and final reproducer, through the transformer 11. The detector tube 10 is shown as of the self-biased type, and the cathode lead of the detector tube includes the usual self-bias resistor 12 which is shunted by the by-pass condenser 13. The numeral 14 represents a source of positive potential for the plate of detector tube 10.

The AVC network includes an electron discharge tube 16 which has its grid 17 connected by way of condenser 15 to the signal grid of detector tube 10. The plate 18 of the AVC tube 16 is connected to a source of positive potential through the resistor 19. The cathode 20 of the AVC tube is the low potential point so far as

signal currents are concerned, and is by-passed by the condenser 21. Resistors 22, 23 and 24 are connected in series across the source of potential 25. A switch 26, having two contacts 27 and 28, is provided, the fixed end of the switch being connected to the junction of resistors 19 and 29.

Contact 27 is connected to the common junction point 36 of resistors 29, 23 and 24. Contact 28 connects to the sliding contact 30, the latter being slideable over resistor 24. The slideable tap 30 is connected by lead 30' to the cathode 20 of tube 16.

When the switch 26 is connected to contact 27, the resistor 29 which has a low value, is short-circuited. The positive potential between the points 20 and 36 across the resistance 24 is applied to the plate 18 through the resistance 19. The bias potential for tube 16 is the voltage between the points 24' and 37 on resistor 24. The slideable tap 30 is adjusted to give a grid bias, as applied to the grid 17 through leak resistor 33, which is several volts below cut-off.

With no incoming signal, no current flows through the resistor 19, and the grid potential of the amplifier tube 8 is the initial bias provided by the voltage drop across the resistor 23. One side of resistor 23 is grounded, as is the cathode of tube 8, and the other side of the resistor is connected through the resistors 19, 34 and the secondary of transformer 7 to the signal grid of controlled amplifier 8.

Now, if an incoming signal reaches the tube 10 with an intensity greater than several volts, this signal transferred to the AVC tube 16 by the condenser 15 will cause current to flow in the plate circuit of tube 16 and through the resistor 19. The voltage developed across the resistor 19 biases the amplifier 8 to a higher value than normal, and so reduces the gain with the result that a control action is developed which tends to prevent further increase in signal.

This same bias voltage may be similarly applied to other of the signal transmission tubes of the receiving system, and preceding tube 8, as is indicated by the AVC lead 35. Plate 18 of the AVC tube is by-passed by the condenser 32 to remove undesired alternating current components, and to improve its rectifying action. Initial adjustment of the point 24' serves to regulate the signal strength at which current begins to flow into the plate circuit of tube 16. After this AVC action begins, little further increase in acoustic output is possible, and consequently the adjustment of the sliding tap 30 determines the volume output of the radio receiver. This volume is then automatically maintained by the above described action.

If the switch 26 is now moved to connect with contact 28, the plate potential is removed from tube 16 and no voltage can be developed across resistor 19 for AVC purposes. The potential existing between the points 36 and 24' is added to the initial bias existing across resistor 23, and serves to bias the amplifier tube 8 and thus regulates the volume. The voltage existing between the points 24'-36 in the AVC position would be too high a bias in the manual volume control position. Hence, the resistor 29 is provided which is connected in shunt between the points 24' and 36 whenever the switch 26 connects to contact 28. This lowers the equivalent resistance between points 24' and 36. By properly choosing the magnitude of the resistor 29, the resulting bias voltage can be made such a value as to cause little

change in the acoustic output, when the switch 26 is moved from the AVC position to the manual control position. Again, with resistor 29 connected between switch points 26 and 27, the 5 switch, and consequently the grid circuit is never completely open. When the switch 26 is in the manual volume control position, movement of tap 30 will change the bias voltage, and hence the volume of the receiver.

10 Fig. 4 shows a curve 38 which gives the plate current of tube 16 through resistor 19 as a function of grid bias. In other words this curve shows the voltage between the points 24' and 37. Various possible operating points 39 to 43 inclusive 15 are indicated. The point 39 is above cut-off; the point 40 is at cut-off; and the other points 41 to 43 inclusive are below cut-off.

Fig. 5 shows a series of curves each marked to correspond with the operating points indicated 20 in Fig. 4. The horizontal dashed line 44 is the cut-off voltage of the amplifier system. If that voltage were obtained from the AVC tube, the amplifier 8 and previous amplifiers would not 25 amplify and no signal would result. As the AVC bias is caused by signal coming through the amplifiers, this extreme condition could not be reached. However, the relative maximum amplitudes approximate the relationship of the intersections of the curves 39 to 43 with the line 30 44. Thus, the greater the negative bias on the grid 17 of the AVC tube, the greater will be the average acoustic output. Therefore, movement of the point 24' on the resistor 24 will regulate the average volume when the switch 26 is connected to contact 27.

Moving the slider 30 towards the upper end 36 of resistor 24 increases the volume in both the manual and AVC positions. Moving the slider 40 30 towards the lower point 37 lowers the volume in both positions. This is not a mere coincidence, but obviously a necessary condition for satisfactory operation of the presently disclosed dual control system. In Fig. 6 there is shown a simple and efficient manner of producing the switching 45 action described in connection with Fig. 3, in an automatic manner. In Fig. 6 the numeral 45 denotes the variable tuning condensers of the receiving system, and the rotors of the variable condensers are mounted on the shaft 46, the shaft 50 carrying the usual tuning dial 47. The shaft 46 may be rotated by engaging the clutch 48 by motion of the shaft 49 towards the condenser 45.

The shaft 49 is constructed to be free to turn in the insulating block 50, and the latter is normally pulled in clutch-opening position by the springs 51 and 52. The bearing 53 is provided, and also acts as a stop for the retaining ring 54. The 5 tuning knob 55 is secured to the shaft 49.

To tune the variable condenser it is necessary to push in the control knob 55 thus engaging the clutch 48. The condenser 45 can then be rotated to any desired position. In so pushing in the 10 knob 55 the insulating block 50 moves forward and operates the switch 56. The contacts of this switch correspond to the points 26, 27 and 28 of the circuit shown in Fig. 3. It will be observed that whenever the condenser can be tuned, the 15 volume control is equivalent to the normal manual control, and consequently the tuning characteristic will be like that of curve 1 in Fig. 1.

Whenever the receiver is being used, but not during the tuning process, the AVC connection 20 is utilized, and so gives its benefit to the operation of the receiver. It will, therefore, be seen that there is thus provided simple and efficient means for tuning in signals in a sharp manner, while providing the advantages of AVC action 25 during the longer and more important listening period.

While I have indicated and described several systems for carrying my invention into effect, it will be apparent to one skilled in the art that my 30 invention is by no means limited to the particular organizations shown and described, but that many modifications may be made without departing from the scope of my invention, as set forth in the appended claim. 35

What I claim is:

In a receiver of the type including an adjustable signal selector, a signal transmission tube, a demodulator, and an automatic gain control tube having control bias connections to said 40 transmission tube, a source of direct current potential connected by electrical connections, including said control bias connections, to the transmission tube to provide normal operating bias therefor, connections from the source to the 45 control tube to energize the latter, and means, responsive to actuation of the selector, for rendering the connections to the control tube ineffective to energize the latter without interference with said normal bias connections. 50

KENNETH W. JARVIS.
